UNITED STATES PATENT OFFICE.

HENRY WILKINSON AND JAMES REED, OF OLDSHAM, ENGLAND, ASSIGNEES OF ONE-
THIRD TO PLATT BROTHERS AND COMPANY LIMITED, OF OLDSHAM, ENGLAND.

CARDING ENGINE FOR CARDING ARTIFICIAL SILK AND SUCH LIKE MATERIAL.

Application filed November 10, 1926, Serial No. 147,430, and in Great Britain January 5, 1926.

Our improvements have reference to carding engines for carding artificial silk, or it might be artificial wool or the like, where the fibres are cut to one uniform length and where it is not requisite that the card shall exercise any particular cleaning effect or have to deal with very short and long fibres at one time.

The object of the invention is to save waste or prevent loss of the valuable material being dealt with, and we effect this by providing and utilizing a revolving covered roller or brush covered with wire or dents or bristles or fibres and which we locate near to the licker-in and there use on the travelling chain of flats. This roller is set to the flats and the cylinder wire, that is contiguous to the dents and is set-in to the same if required, and, by its action, fibres remaining on the travelling flats after leaving the cylinder are not stripped off so as to become waste but are returned by said covered roller to the main cylinder for incorporation or blending with fibres entering the card and not yet operated on by the flats. As thus, the fibers stripped from the flats are put back onto the incoming new material. The flats which are in carding contact with the main cylinder travel towards the licker-in, or they may travel in the contrary direction. Such a single roller arrangement serves for working with some classes of fibre but with other classes of fibre we use in combination with the before described covered roller (and to effectively deal with any fibre still remaining on the "flats" and depending or hanging down) a revolving brush which is set to the revolving flats and the before described roller, the same having bristles, dents or wires, fibre or other clothing and the bristles may be set slightly into the flats and be cleared of any fibre by the before described roller and the fibre returned to the main cylinder.

Provision is made for driving both roller and brush, the latter lying in front of the former looking from the front of the card. Plain under sheetings for the licker-in and main cylinder are also preferably provided with advantage, as later indicated.

The drawing accompanying and forming part of this specification is a diagrammatic side view of a machine illustrating one embodiment of our invention.

Referring to the drawing, according to our invention and in connection with revolving

flat cards for the indicated purposes, we no longer use a flat stripping comb which removes the material in the form of "flat stripings," but we apply a revolving covered roller, or revolving brush *a* suitably clothed and this is located near to the licker-in *b* and intermediate of the flats *c* and main cylinder *d* and this covered roller *a* is mounted and driven so as to strip the flats and deposit the material on the main cylinder whereby the valuable stripings are deposited on the new material being carried up by the main cylinder. In combination with the covered roller *a* just described, and in connection with same and the flats we employ a revolving brush or stripper *a'*, the covered roller *a* and the brush *a'* revolving in the same or either direction. The flats over the cylinder in this case revolve towards the licker-in.

With the need for economy we can with advantage return the artificial silk or material of regular or even length of fibre and free from impurities by a revolving covered device *a* which simultaneously strips the flats and feeds the saved material for blending or combining with fresh supplied material. In the arrangement herein illustrated, however, the action of the combined revolving brush *a'* along with the covered roller *a* deals effectively with any fibres escaping the first stripping action.

Also, with the object of effecting further economies, we prefer to dispense with more knives and grids below the licker-in *b* and to use a plain bent sheet or sheets *b'* of metal plate in lieu thereof, the same being supported from setting brackets and being adjusted to leave a narrow space between the plain sheet and the revolving licker-in so that again material cannot escape, and economies are effected. Also, for the purpose of preventing waste of fibres, a plain bent sheet or sheets *d'* of metal plate in lieu of a grid may be used below the main cylinder *d* and supported in any convenient manner.

The features of our invention become feasible for effective working by reason of the fact that the material dealt with carries no impurities and there is no great variation in the length of fibres being carded at any one time. The arrangement described allows us to save and re-introduce automatically into the card, material which would otherwise be wasted.

We declare that what we claim is:

In revolving flat carding engines for carding artificial silk, the combination with a main cylinder and rotating flats, of means for stripping the flats at the taker-in end and returning the stripped material at once and directly to the main cylinder, said means comprising a rotating covered roller inter-

mediate of and contacting with the flats and the main cylinder, and a rotating clothed stripper between said roller and the flats.

In testimony whereof we have signed our names to this specification:

HENRY WILKINSON.
JAMES REED.
